(57) **CLAIM**

The ornamental design for a drill-less window air conditioner bracket, as shown and described.

DESCRIPTION

FIG. 1 is a front perspective view of the drill-less window air conditioner bracket, showing my new design;

FIG. 2 is a front elevation view thereof;

FIG. 3 is a rear elevation view thereof;

FIG. 4 is a left side elevation view of the drill-less window air conditioner bracket, the right side being a mirror image thereof;

FIG. 5 is a top plan view thereof;

FIG. 6 is bottom plan view thereof;

FIG. 7 is a front perspective view of the drill-less window air conditioner bracket shown in use; and,

FIG. 8 is a front perspective view of the drill-less window air conditioner bracket shown in a collapsed position.

The broken lines in the drawings illustrate portions of the drill-less window air conditioner bracket which form no part of the claimed design.
